UNITED STATES PATENT OFFICE.

GEORGE A. ROBERTS, OF WOLLASTON, MASSACHUSETTS.

FELT POLISHING-STICK.

1,105,457.

Specification of Letters Patent. Patented July 28, 1914.

Application filed January 29, 1913. Serial No. 744,942.

To all whom it may concern:

Be it known that I, GEORGE A. ROBERTS, a subject of the King of Great Britain, residing at Wollaston, in the county of Norfolk 5 and State of Massachusetts, have invented new and useful Improvements in Felt Polishing-Sticks, of which the following is a specification.

This invention relates to reinforced felt 10 polishing sticks; and it has for its object the provision of a device of this character which will be designed particularly for use in polishing heading-dies or like tools, and which is also constructed whereby it may be 15 used by dentists for polishing the teeth and for removing discolorations or tartar therefrom and for polishing gold crowns and bridge work.

Another object of the invention is to provide 20 a polishing stick which will include an elastic polishing element and a rigid holder therefor, the latter being associated with the former whereby a part thereof of minimum proportion may be exposed so as to permit 25 of its being effectually applied to the work.

A further object of the invention is the provision of a polishing stick wherein the 30 cleaning element thereof is formed of compressible material, such as felt, which may be compressed and fed spirally into the receiving bore of the holder in a convenient manner in the manufacture of the article.

With these and other objects in view, the 35 invention consists of certain novel features of construction, combination and arrangement of parts, as will be hereinafter described and claimed.

In the accompanying drawings:—Figure 40 1 is a side view of the polishing stick; and Fig. 2 is a vertical longitudinal section therethrough.

With a view to providing a polishing stick 45 wherein the polishing element thereof will be reinforced throughout its length and so arranged that a very small portion thereof may be exposed for proper application to the work to be polished, I provide a holder 1, which is preferably constructed of wood

and provided with a longitudinal bore 2 which opens onto one end of the holder, as 50 clearly shown. The exterior surface of the holder is provided with marked portions such as the circles 3, which are equi-distantly arranged relatively and which extend along the support through the length of the bore 2 55 for a purpose to be hereinafter described.

The polishing material 4 comprises a single length of compressible material, such as felt, or the like which in the initial manufacture of the article may be compressed and 60 gradually fed spirally into the receiving bore of the holder 1. The polishing material has a length initially greater than the depth of the receiving bore of the holder, so that the effective polishing end of the material 65 may be properly exposed for use. At the open end of the bore, the material of the holder 1 is sharpened or pointed, as at 5, so as to permit the polishing material to be properly exposed during the operation of 70 polishing small objects. The external indicating surfaces on the holder 1 are to designate the termination of the polishing material in the holder and to indicate proper points in the length of the holder that may 75 be touched and sharpened, so as to expose the polishing end of the polishing material, as the latter becomes worn. In other words, the holder may be sharpened at the discretion of the operator as in the operation of 80 sharpening a pencil to expose the lead.

It is obvious that the device may be made in any required length or diameter as may be necessary to adapt them to a particular use.

While the device is designed especially to be manipulated by the hand, it is also obviously intended that the same may be used in a suitable holding device such as a spring chuck or screw center in a polishing-head or lathe where it may be revolved and subjected directly to the work to be polished or applied as the latter is revolved in any well known manner.

From the foregoing description, taken in 95 connection with the accompanying draw-

ings, the construction and operation of the invention will be readily understood without requiring a more extended explanation.

Having thus described my invention,

5 what I claim is:—

In a device of the character described comprising an elongated stick, provided with a tapered end, said stick being formed with a longitudinal cylindrical bore open-

10 ing out of its tapered end, and a fibrous strip of a slightly larger diameter than the

diameter of said bore, said fibrous strip having its body spirally expanded within said bore and having a greater length than said bore.

In testimony whereof I affix my signature in presence of two witnesses.

GEORGE A. ROBERTS.
